REAR INDEX CARD AND HOLDER FOR
VISIBLE INDEXESRobert W. Riggs, Stamford, Conn., assignor to
Remington Rand, Inc., Buffalo, N. Y., a corpora-
tion of Delaware

Application December 21, 1946, Serial No. 717,784

2 Claims. (Cl. 129—16.7)

1

This invention relates to improvements in visible card indexes and particularly to improvements in means for holding a card on the rear side of a card holder.

The invention provides an index card for the rear side of the card holder of a conventional form of visible index for support on the rear side of the card holder without notching the margin of the card to receive the center stitch that holds the transparent tip on the card holder. The invention obtains this result by employing a notched insert inserted into the transparent tip of a conventional card holder on the rear side to provide a marginal portion extending beyond the tip to provide a rear card retaining flange for receiving a margin of the rear index card to detachably retain it on the card holder. The insert is notched in the central portion to receive the center stitch at the rear side of a card holder that secures the transparent tip to the supporting sheet. The free ends of the card retaining insert are also provided with projections for cooperation with the means that secures the ends of the tip to the supporting sheet of the card holder in order that the insert is held in interlocked relation on the card holder against accidental detachment.

In the drawings:

Fig. 1 shows a conventional card holder having the hinged portion rotated on its hinge into an upwardly extending position relative to the supporting lug to illustrate the rear side of the card holder with the notched insert and record card applied to the rear side of the card holder.

Fig. 2 is an enlarged cross section taken on line 2—2 of Fig. 1.

Fig. 3 is an enlarged cross section taken on lines 3—3 of Fig. 1.

Fig. 4 is an enlarged cross section taken on line 4—4 of Fig. 1.

Fig. 5 shows the notched insert formed with the rear card retaining flange in perspective.

The invention is applied to a conventional form of card holder having a supporting sheet 1 provided with a row of openings 2 arranged in a line spaced inwardly from one edge of sheet 1. These openings 2 separate a marginal portion along one edge of sheet 1 for attachment to lug 3 having the ends extending beyond the side edges of sheet 1, as shown in Fig. 1. The ends of the lugs may be engaged in the channels on a supporting structure for the card holder. A plurality of card holders are mounted in overlapping offset relation through the cooperation of lugs 3 thereon in a manner well known in the art to support index cards on the front faces of sheet 1 with their free margins in visible indexed relation. The major portion of supporting sheet 1 is hingeable relative to the marginal portion secured to lug 3 so that this major portion of supporting sheet

1 may be moved into the position shown in Fig. 1 to expose a card supported on the rear face. Supporting sheet 1 is formed with diagonal slots 4 adjacent hinge openings 2 for receiving the corners of record cards in interengaged relation on both sides of supporting sheet 1 in order to retain one margin attached to the card holder.

The free margin of supporting sheet 1 is embraced by a folded strip of transparent plastic material forming a tip 5 having a front fold portion 6 provided with an inturned lip 7 on the free edge thereof, as shown in Figs. 2 and 3. The rear fold 8 engages the rear face of supporting sheet 1, in the manner shown in Figs. 1 to 4 so that it lies substantially flat against the rear face of sheet 1. Wire stitches 9 are inserted through both the front and rear folds 6 and 8 respectively, of tip 5 and supporting sheet 1 to rigidly secure the tip in position on the free margin of supporting sheet 1. The corners of supporting sheet 1 are usually cut out to receive the end of wire stitch 9 extending through the front and rear folds 6 and 8 of tip 5 while the other end of stitch 9 engages only supporting sheet 1 providing for compensation for differences between the coefficients of expansion of sheet 1 and tip 5, in a manner well known in the art. The central portion of rear fold 8 of tip 5 has the central portion of the margin thereof secured to supporting sheet 1 by a wire staple 10, in the manner shown in Figs. 1 and 2. One end of the staple extends through fold 8 and sheet 1 while the opposite end extends beyond the edge of fold 8 where it extends through sheet 1 only.

35 A rectangular imperforate record card 11 may have one margin engaged under front fold portion 6 of tip 5 and the corners of the opposite margin extended through slots 4 in supporting sheet 1 for supporting card 11 on the front face of supporting sheet 1 so that the margin covered by the fold portion 6 of tip 5 will normally lie in visible index relation where a series of record cards are supported by a series of card holders arranged in overlapping offset relation to provide a visible index.

45 Record cards have also been placed on the rear face of these conventional card holders. They require the notching of the central marginal portion at the position where wire stitch 10 is located in order that the remaining marginal portion of a rear card may be inserted between rear fold 8 of tip 5 and the marginal portion of supporting sheet 1. Due to the rear fold portion 8 lying substantially flat against the rear face of supporting sheet 1 it is difficult to insert a card margin under fold portion 8, particularly in view of the free edge portion fold 8 being closely secured to supporting sheet 1 by staple 10.

50 The present invention is designed to eliminate the difficulty experienced with the present com-

mercial visible card indexes in placing a card on the rear face of the card holder.

The improved construction includes the provision of an insert 15 in the form of an elongated paper strip having a width greater than the width of the rear fold portion 8. Strip 15 is engaged under fold portion 8 so that the edge engaged in tip 5 will extend to the folded portion of the tip in substantially coincident relation with the free margin of supporting sheet 1, as shown in the drawing. The central portion of insert 15 is notched at 16 to receive central staple or wire stitch 10 while the opposite margin of insert 15 is formed with an inturned lip 17 to provide a rounded edge that will facilitate the insertion of a record card margin under inturned lip 17. This last mentioned edge of insert 15 extends inwardly toward the central portion of supporting sheet 1 beyond the inner edge of rear fold portion 8 of tip 5 a sufficient distance to provide the rear card retaining flange 18.

The ends of insert 15 are provided with projections 19 that are adapted to extend between staples 9 and the outer fold portion of tip 5, in the manner shown in Fig. 1, to interlock insert 15 with the card holder to normally prevent its removal from tip 5. By flexing insert 15 to shorten the distance between the ends sufficiently, projections 19 may be easily inserted under wire stitches 9 in applying the insert into the position shown in Fig. 1 on the card holder. This insert is normally allowed to remain attached to the card holder to provide rear card retaining flange 18 thereon.

Then, a rear record card 20 is provided for the card holder having a rectangular imperforate form so that a conventional rectangular record card can be used and applied on the rear side of the card holder without having to notch the outer margin to receive central wire stitch 10. Record card 20 has one margin engaged under rear card retaining flange 18 of insert 15. The edge of card 20 does not extend into tip 5 but only under flange 18 to a position approaching the edge of rear fold 8, as shown in Figs. 2 and 3. Then, the opposite margin of rear record card 20 may have the corner portions engaged in slots 4 near hinge openings 2, as shown in Fig. 1 to detachably mount card 20 on the rear face of the card holder.

With this construction of insert to provide rear card holding flange 18, record card 20 can be very quickly and efficiently applied in position for support on the rear side of the card holder by first inserting one margin under flange 18 and then engaging the opposite corners in diagonal slots 4. The rounded edge on flange 18 provided by inturned lip 17 facilitates the insertion of the margin of record card 20 under flange 18.

This improved construction for mounting a record card on the rear side of a conventional card holder considerably reduces the cost of providing visible indexes with rear record cards both from the standpoint of the original installation of the inserts and cards in the card holder and also effects a substantial saving in labor in operation by reducing the amount of time required in removing and replacing cards for making entries and checking purposes according to the usual operation of visible index record installations.

The invention claimed is:

1. In a card holder having a supporting sheet, means on one margin thereof for attachment to a support, a hinge formed in said margin so the remainder of said sheet may be swung on said hinge relative to said margin, a folded transparent tip of sheet material embracing the opposite margin of said sheet to form retaining flanges on both sides thereof, said tip having an inturned lip on the front marginal portion thereof, means securing the ends of the fold portions of said tip to said sheet, means securing the central portion of the margin of said tip at the back side of said sheet thereto, and card holding means on said sheet adjacent said hinge for holding card margins on both sides of said sheet adjacent said hinge, the combination of an insert formed of a strip engaged in said tip at the back side of said sheet formed with a slot to receive said means 15 securing the central portion of said tip to said sheet and having a margin thereof projecting beyond said tip toward said hinge to provide a rear card retaining flange, and an index card detachably retained on the rear side of said card holder with opposite margins retained by said retaining flange and card holding means respectively.

2. In a card holder having a supporting sheet, means on one margin thereof for attachment to a support, a hinge formed on said margin so the remainder of said sheet may be swung on said hinge relative to said margin, a folded transparent tip of sheet material embracing the opposite margin of said sheet to form retaining flanges on both sides thereof, said tip having an inturned lip on the front marginal portion thereof, means securing the ends of the fold portions of said tip to said sheet, means securing the central portion of the margin of said tip at the back side of said sheet thereto, and card holding means on said sheet adjacent said hinge for holding card margins on both sides of said sheet adjacent said hinge, the combination of an insert formed of a strip material having one margin engaged between said tip and the margin of said sheet, said insert having a slot in said one margin receiving said means securing the central portion of said tip to said sheet, the opposite margin of said insert projecting outwardly beyond the edge of said tip to provide a rear card retaining flange, said insert having projections at opposite ends engaged in interlocking relation with said means securing the ends of said tip to said sheet, and a rear index card supported at the rear side of said sheet with one margin detachably engaged between said sheet and rear card retaining flange of said insert and the opposite margin detachably engaged with said card holding means.
